United States Patent Office

Des. 223,941
Patented June 20, 1972

223,941

ILLUMINATING TOY

John R. Parsons, 1425 Lincoln Ave. NE,
Renton, Wash. 98055

Filed June 22, 1970, Ser. No. 23,590

Term of patent 3½ years

Int. Cl. D21—01

U.S. Cl. D34—15

The figure is a perspective view of the illuminating toy embodying my new design.

I claim:

The ornamental design for an illuminating toy, as shown.

References Cited

Playthings, March 1967, p. 65, Playskool Advt.

MELVIN B. FEIFER, Primary Examiner